(57) **CLAIM**

The ornamental design for a vehicle wheel, as shown and described.

DESCRIPTION

This application contains subject matter related to the following co-pending U.S. design patent application:
 Application Ser. No. 29/491,043, filed May 16, 2014 and entitled “Vehicle Wheel.”

FIG. 1 is a perspective view of a vehicle wheel according to the design;

FIG. 2 is an additional perspective view thereof;

FIG. 3 is an additional perspective view thereof;

FIG. 4 is a front view thereof;

FIG. 5 is a rear view thereof in a lighter gray scale, representing environmental features that form no part of the claimed design; and,

FIG. 6 is a side view thereof.

1 Claim, 6 Drawing Sheets(56)
